US00D820862S

(12) **United States Design Patent** (10) Patent No.: **US D820,862 S**
 Alfonzo et al. (45) Date of Patent: ** Jun. 19, 2018

(54) **DISPLAY SCREEN OR PORTION THEREOF WITH GRAPHICAL USER INTERFACE**

(71) Applicant: **Lutron Electronics Co., Inc.**,
 Coopersburg, PA (US)

(72) Inventors: **Karelys Alfonzo**, Coopersburg, PA (US); **Rhodes B. Baker**, Bethlehem, PA (US); **John H. Bull**, Coplay, PA (US); **Erica L. Clymer**, Nazareth, PA (US); **Sanjeev Kumar**, Harleysville, PA (US); **Aaron Peters**, Allentown, PA (US); **Rahul Subramany**, Hellertown, PA (US); **Shannon M. Sullivan**, Coopersburg, PA (US)

(73) Assignee: **Lutron Electronics Co., Inc.**,
 Coopersburg, PA (US)

(**) Term: **15 Years**

(21) Appl. No.: **29/562,239**

(22) Filed: **Apr. 24, 2016**

(51) LOC (11) Cl. **14-04**

(52) U.S. Cl. **D14/486**
 USPC ..

(57) **CLAIM**

The ornamental design for a display screen or portion thereof with graphical user interface, as shown and described.

DESCRIPTION

The sole FIGURE shows a display screen or portion thereof with graphical user interface showing our new design. The dashed broken lines represent a display screen or portion thereof and form no part of the claimed design.

1 Claim, 1 Drawing Sheet
